UNITED STATES PATENT OFFICE.

FREDERICK J. LANDER, OF ROCHESTER, NEW YORK.

SYRINGE.

SPECIFICATION forming part of Letters Patent No. 655,657, dated August 7, 1900.

Application filed October 11, 1899. Serial No. 733,283. (No model.)

To all whom it may concern:

Be it known that I, FREDERICK J. LANDER, a citizen of the United States, residing at Rochester, in the county of Monroe and State 5 of New York, have invented certain new and useful Improvements in Vaginal Syringes; and I do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 The invention relates to an improvement in the vaginal syringe patented to me September 12, 1899, and numbered 632,728.

Figure 1 of the drawings is an elevation showing my syringe after all the parts have 20 been attached together; Fig. 2, an elevation of the injector; Figs. 3 and 4, details showing, respectively, a shield without the extension-plate and one provided with it; Fig. 5, a perspective view of the wire cage, showing 25 how the upper ends of the wires are secured to the head of the screw; and Figs. 6, 7, 8, and 9 are detail views, respectively, of the cage-screw, the receiving-cup, the disk in the lower end of the cup, and the central metallic tube through which pass the inflow and 30 the outflow of the liquid or medicine.

In the drawings, A represents the wire cage; B, the central tube; C, the receiving-cup into which is discharged the liquid carrying the impurities, and D the shield, which 35 forms a tight joint with the outside of the vagina, and thus prevents any escape of the outflowing liquid.

E represents an injector with a neck e to 40 fit on the pipe c of the receiver C, or I may use the ordinary water-bag instead of the bulb-injector.

The wire cage or distender of the interior parts has the upper ends of the wires curved

inwardly and secured in side holes of the 45 head of the screw F, which hangs centrally among the wires. These wires being elastic thus hold the screw firmly, are maintained in their true relative position, and yet allow the screw to be readily detached from them. 50

The tube B has an internal thread at the upper end to work on the screw F and near the lower end a collar b, which makes a close joint at the hole g of the disk G, which forms the bottom of the receiver C. b' is the end knob 55 of the tube B, over which tightly fits the neck e of the injector. b² shows a series of rows of holes in the side and near the upper end of the spraying-tube B, which rows may be four or more in number, so as to insure the contact of the liquid with the whole interior surface of the vagina at the points desired. 60

The receiver C has inwardly-inclined fingers c', and between these pass the cage-wires, while its bottom G rests centrally upon the 65 collar b, the receiver being thus securely held in place. Upon this receiver slides my shield D, which is crimped on the receiver sufficiently to stay in place wherever it is adjusted against the person, so as to form a 70 tight joint therewith. d is an extension-plate.

What I claim as new, and desire to protect by Letters Patent, is—

A syringe having the cage-wires bent at 75 their front ends toward each other, a screw with which said front ends engage, a receiver having a disk bottom centrally open and an outlet-pipe at its lower end, a spraying-tube connected to the said screw, and a shield adjustable on the receiver, all combined and arranged substantially as shown and described. 80

In testimony whereof I have affixed my signature in presence of two witnesses.

FREDERICK J. LANDER.
